LETTER OPENER

Alex A. Kriewaldt, Oconto, Wis., assignor of one-half to Harold W. Krueger, Oconto, Wis.

Application August 5, 1944, Serial No. 548,202

1 Claim. (Cl. 30—289)

The present invention relates to new and useful improvements in a stationery device particularly for desk use, and has for its primary object to provide a letter opener including a blade and unique means for firmly securing said blade in position whereby an edge thereof may be used.

Other objects of the invention are to provide an article of the character set forth which will be comparatively simple in construction, strong, durable, compact, attractive in appearance and which may be manufactured at low cost.

All of the foregoing and still further objects and advantages of the invention will become apparent from a study of the following specification, taken in connection with the accompanying drawing wherein:

Figure 1 is a top plan view of a device constructed in accordance with the present invention.

Figure 2 is an elevational view, looking at one end of the device.

Figure 3 is an elevational view, looking at the other end of the device.

Figure 4 is a view in transverse section.

Referring now to the drawing in detail, it will be seen that the embodiment of the invention which has been illustrated comprises a substantially rectangular body or block 1 of suitable material, which block may be of any desired dimensions. Extending from end to end of the block 1 in the top thereof and adjacent the longitudinal sides of said block are grooves or channels 2. The end portions of the grooves 2 are laterally offset relative to each other, providing oblique intermediate portions 3.

Between the grooves 2 an intermediate portion of the block 1 is cut away in a manner to provide a depression or recess 4 which communicates throughout its length with said grooves. The recess 4 is shallower than the grooves 2. The recess 4 is for the reception of a double-edged removable blade 5 which is so positioned that the end portions of the cutting edges thereof extend obliquely across the grooves 2.

An elongated bar 6 fits into the recess 4 for clamping the blade 5 in position. The longitudinal edges of the bar 6 conform to the opposed outer walls of the grooves 2. A screw 7 secures the bar 6 in position. The blade 5 is mounted between gaskets 8 of suitable material. The screw 7 passes through openings which are provided therefor in the members 6, 8 and 5 and is threaded into the block 1.

On one end portion of the block 1 is a pencil sharpener 9. The sharpener 9 includes a substantially conical socket 10 for the reception of a pencil, said socket 10 extending into said block 1 from one end thereof and communicating with the top of said block. A blade 11 is recessed into the top of the block 1 in a manner to be flush

therewith and said blade projects over the socket 10.

Extending longitudinally into the block 1 from the other end thereof is an elongated chamber 12 for the reception of a supply of mechanical pencil leads. A screw plug 13 closes the lead chamber 12. The lead chamber 12 is located between one of the longitudinal sides of the block 1 and the adjacent groove 2.

It is thought that the manner in which the device is used will be readily apparent from a consideration of the foregoing. When a paper weight is desired, the block 1 serves as such. Any suitable advertising or other matter may be carried on the lower face of the block 1. To sharpen a pencil, said pencil is inserted in the socket 10 in engagement with the cutting edge of the blade 11. The block 1 is then turned in an obvious manner while the pencil is held stationary for causing the blade 11 to put a point on said pencil. By engaging one end portion of an envelope in either of the grooves 2 and then pulling the block 1 along an edge of the envelope, said envelope may be rapidly and neatly opened without damaging the contents thereof through the medium of the blade 5. As hereinbefore stated, the cutting edges of the blade 5 extend diagonally across the grooves 2 for cutting off the lower portions of the envelopes as the block 1 is moved thereon. By simply removing the screw 7 and the bar 6, the blade 5 may be conveniently reversed or removed for replacement.

It is believed that the many advantages of a combination stationery device constructed in accordance with the present invention will be readily understood, and although a preferred embodiment is as illustrated and described, it is to be understood that changes in the details of construction may be resorted to which will fall within the scope of the invention as claimed.

What is claimed is:

A device of the character described comprising an elongated block having a groove in its top portion extending from end to end thereof, said groove including laterally offset end portions and further including a substantially oblique intermediate portion connecting said end portions, the block further having a recess in its intermediate top portion communicating with the groove, a blade mounted in the recess and having its cutting edge extending obliquely across the groove at a point adjacent the substantially oblique intermediate portion of said groove, a bar mounted in the recess and engaged with the blade, and a screw passing through the bar and the blade and threaded into the block for securing said bar and said blade in position.

ALEX A. KRIEWALDT.
